UNITED STATES PATENT OFFICE.

IRA C. BUCKMINSTER, OF BEVERLY, MASSACHUSETTS, ASSIGNOR TO UNITED SHOE MACHINERY COMPANY, OF PATERSON, NEW JERSEY, A CORPORATION OF NEW JERSEY.

WORK-SUPPORT.

1,133,533.

Specification of Letters Patent. Patented Mar. 30, 1915.

Application filed May 13, 1912. Serial No. 696,953.

To all whom it may concern:

Be it known that I, IRA C. BUCKMINSTER, a citizen of the United States, residing at Beverly, in the county of Essex and State of 5 Massachusetts, have invented certain Improvements in Work-Supports, of which the following description, in connection with the accompanying drawings, is a specification, like reference characters on the drawings indicating like parts in the several figures.

This invention relates to work supports, and more particularly to a support for a last such as is used to hold a shoe while various operations are performed upon it during the process of its manufacture. In a 15 type of heel attaching machine in common use the last, upon which the shoe is held while a heel is being attached to it, is carried by a swinging jack post which moves, longitudinally of the shoe, from an inoperative position, where the shoe is jacked, to a definite operative position, where the heel is attached to the shoe. The heel is supported 20 separately with its top lift or tread face in a definite, fixed position. When attaching heels of various heights and pitches it becomes necessary to adjust relatively the heel and shoe, longitudinally of the shoe, in 25 order to secure proper register between the seat face of the heel and the heel seat of the shoe.

It is the purpose of the present invention to provide a work support with means movable relatively to the support for permitting 35 quick and easy adjustment and accurate location of the work in such a position as may be necessary or desirable. To this end, an important feature of the invention consists in a last carrying device which is mounted upon a movable jack or supporting element in such a manner as to permit adjustment of the shoe longitudinally with 40 relation to the jack, which is moved always to a definite position. The last carrying device is preferably in the form of a plate provided with a heel pin to receive a wood last and freely movable relatively to the jack through a limited distance longitudinally of 45 the last. An adjustable back stop is provided against which the rear end of the shoe is placed to assist in locating it properly when the jack is moved into its operative position. The last plate may be mounted 50 upon the jack post in any suitable man-

ner to permit the required relative movement between the parts without allowing them to become separated, but it has been found convenient to employ a T-shaped tongue and slot connection with a stop pin 60 to limit the extent of the movement.

A further feature of the invention consists in mounting the last plate for free movement in a plurality of directions in a single plane, so that the shoe may easily 65 take a position determined by suitable gages or stops, without the necessity of making adjustments of the jack. It is found convenient to provide for universal movement of the last plate in a single plane by using 70 between it and the jack post a connecting member having two tongue and slot connections with the jack post and last plate respectively at right angles to each other.

In the drawings and the detailed description to follow the invention is illustrated and described as embodied in a work support for wooden lasts to be used in a heel attaching machine but it should be understood that this is merely for the purpose of 75 illustration and that the invention may be embodied in other specific forms and used in other machines without departing from its spirit and intent, as defined by the 80 claims.

In the drawings,—Figure 1 is a perspective view of a work support embodying one form of the invention; and Fig. 2 is a central, vertical longitudinal view, partly in section, of the parts shown in Fig. 1.

Referring to the drawings, a jack post 10 is pivoted at 12 to swing in a vertical plane. The lower end of the jack post is split at 14 and a corrugated block 16 is secured permanently within the split portion. A block 18 fitting loosely in the lower end of the jack post has its curved upper edge corrugated to coöperate with the block 16. A curved slot 20 is provided through which a screw 22 passes. The screw 22 passes through one side of the lower portion of the jack post and is tapped into the other side, so that it serves, when tightened, to draw the two sides toward each other, clamping the block 18 tightly between them. The slot 20 is 100 somewhat wider than the diameter of the screw 22 in order to permit the block 18 to be lowered until the corrugated surfaces of said block and the block 16 are out of engagement when it is desired to adjust the 105 110

block forwardly or rearwardly. It will be seen that the construction is such as to permit the block 18 to be adjusted angularly in a vertical plane and to be held securely in 5 any desired position of adjustment.

The lower face of the block 18 has a transverse undercut groove adapted to receive the dovetail 24 formed upon the last supporting member or last bed piece 26. A transverse 10 recess 28 in the upper face of the last bed piece receives the end of a spring-pressed pin 30 which is provided with a button 32 located for convenient hand operation. The recess 28 is long enough to allow considerable 15 sidewise movement of the last bed piece 26 while preventing the latter from dropping out of its supporting block accidentally.

A T slot 34 is formed in the lower face of the last bed piece 26 and a last plate 36 having 20 an upwardly projecting T-shaped portion is supported in the last bed piece for longitudinal sliding movement, the extent of which is limited by a pin 38 secured in the last bed piece and projecting into an elongated 25 recess 40 in the upper face of the last plate. A pin 42 secured in the plate 36 receives the last 44 carrying the shoe 46 to be operated upon.

The pivot pin 12 is mounted in two wings 30 48 projecting downwardly from a plate 50 which supports the jack post and all the mechanism which has been hereinbefore described. The upper end of the jack post 10 is formed with a flat portion 52 which engages 35 the lower side of the plate 50 when the post is in its innermost position ready for operation, as illustrated in Fig. 2.

It is usually desirable to clamp or hold the shoe firmly while it is being operated upon, 40 and this is well illustrated in the case of the heel attaching machine which has been selected for the purpose of illustrating a specific embodiment of the invention. In such a machine a nail block 54 is so located 45 that when the shoe is in position to be operated upon, as shown in the drawings, movement of either the jack or the nail block toward the other will clamp and hold the work firmly. When a pivoted jack is employed 50 it is desirable that the line of application of pressure to the work should be such as not to have a tendency to cause the work to be thrown out of position. The stop surface 52 is therefore so arranged that 55 when the jack is pushed in as far as possible its center line will be somewhat back of the line A—B of relative movement of the parts. With this construction the tendency, when 60 pressure is applied to the work, is to force the work more firmly into the machine rather than to cause it to be "kicked" out forwardly.

It is customary to hold a heel 56 upon the nail block 54 by means of a holder having a 65 normally fixed rear gage 58 and a yielding

front gage 60. This arrangement holds the rear portion of the heel near its tread face in a predetermined fixed operative position.

It is necessary that the heel seat portion of the sole of the shoe be brought properly 70 into register with the heel seat face of the heel before the heel is attached or before any other operation is performed upon the work. This location of the shoe in the machine illustrated is effected by a band clamp comprising a flexible member 62 of thin sheet metal supported at its sides by links 64 carried by adjustable brackets 66. The central portion of the flexible member 62 is supported in a block 68 which, in turn, is carried upon the end of a pin 70. The pin 70 is freely slidable in a bushing 72 which screws into a suitable bracket or supporting member 74. The front end of the bushing 72 serves as an adjustable stop to limit rearward movement of the block 68 and therefore serves to determine the rearmost position to which the shoe may be pushed.

Heels vary greatly in size, height and pitch. Since the nail block is immovable 90 longitudinally of the shoe and since the tread face of the heel must be located in a predetermined relation to the nail block, it is apparent that the position of the rear edge of the heel seat surface of the heel will 95 vary considerably with different sizes and styles of heels. It is therefore necessary to provide means for adjusting the rearward limit of movement of the shoe as described in order to make it possible to secure perfect register between the shoe and heel. Since, for reasons previously stated, the jack must always move to the same position, provision 100 must be made for relative movement, longitudinal of the shoe, between the shoe and the jack post. This is further necessitated by the fact that the pin holes in different lasts frequently vary considerably in location so that in using two successive lasts of the same size and style it may be necessary to move 105 the last pin 42 into different positions. The variation in the location of the pin hole in the last not only occurs longitudinally of the last but also transversely. Furthermore, 110 there are many styles of lasts in which the pin hole purposely is not centrally located transversely of the last. Under such circumstances, it is necessary that the relative adjustment of the shoe and heel both laterally and longitudinally be effected by gages 115 which are arranged for contact with the surface of the work, and that the work support or jack be constructed for self adjustment to any size or style of last which it may be necessary to handle. From these considerations it will be seen that a limited universal movement of the heel pin in a horizontal plane is requisite in order to secure perfect 120 results when operating the machine, and the construction should be such that this self

125 130

adjusting movement may take place automatically, since the location of the heel pin may vary with every shoe to be operated upon.

5 While the invention has been illustrated and described as embodied in a heel attaching machine, it should be understood that it may be adapted to other machines in which a shoe is supported in a similar manner for operations to be performed upon it, and that the invention is not limited in its application to the specific machine referred to in the detailed description.

Having described my invention, what I 15 claim as new and desire to secure by Letters Patent of the United States is:—

20 1. In a heelng machine, the combination of a jack post movable from an inoperative position to a fixed operative position, means for locating a shoe for operation thereon, and a last plate carried by said jack post constructed and arranged for free and unobstructed movements in a plurality of directions in a single plane responsive to said 25 locating means as the jack is moved to its fixed operative position to automatically position the shoe.

2. In a heelng machine, the combination of a jack post movable longitudinally of the machine from an inoperative position to a fixed operative position, a last plate carried by said jack post, a pin on said last plate adapted to receive a last, and a back stop arranged to be engaged by a shoe upon said 35 last when the jack is in operative position, said last plate being constructed and arranged for free longitudinal movement independently of the jack, whereby the shoe may be brought automatically into position 40 responsive to the demands of the back stop irrespective of variations in the last.

3. In a machine of the class described, the combination of a jack pivoted to swing between a shoe receiving position and a fixed 45 operative position, a last engaging and supporting member on the jack constructed and arranged for free and unobstructed movement in all directions in a plane transverse to the longitudinal axis of the jack, and a member having longitudinally and laterally adjustable portions for locating a last supported by said freely movable member as the 50 jack is moved to its fixed operative position.

4. In a heelng machine, the combination 55 of a nail block and a jack relatively movable in a right line toward and from each other, the jack being mounted for pivotal movement between a work receiving position at an angle to said right line upon one side thereof and a fixed operative position at an angle to said line upon the opposite side thereof, independently mounted, adjustable means for locating the work relatively to the nail block, and a last engaging member upon 60 the jack mounted to permit the work to ad-

just itself freely to the locating means when the jack is in said fixed operative position.

5. In a heelng machine, the combination of a jack post movable from an inoperative position to a fixed operative position, means 70 including a flexible band to engage and locate the rear portion of a shoe upon the last, and a last supporting member mounted upon the jack post for movement in a plurality of directions in a single plane by contact of 75 the shoe with said flexible band as the jack is moved to its fixed operative position.

6. In a heelng machine, the combination of a jack post movable from an inoperative position to a fixed operative position, a last plate having a last pin to engage the last pin socket in a last and a pressure bearing portion to engage the top or crown of the last and take the pressure transmitted thereto, an independently mounted back stop, and connections between the last plate and jack post 80 constructed and arranged to permit free movement of the last plate in a plurality of directions in a single plane as the jack post is moved to place the shoe against the back 85 stop.

7. In a heelng machine, the combination of a jack post movable from an inoperative position to a fixed operative position, a last plate 90 tiltable in a plane passing through the longitudinal axis of the jack post and having a last pin and a pressure bearing portion to engage the top or crown of a last positioned on said last pin, means independent of the jack post to position a shoe thereon, and 95 connections between the jack post and last plate constructed and arranged to permit free movement of said plate in a plurality of directions in a single plane as the jack is moved to its fixed position to place the shoe 100 in contact with the positioning means.

8. In a heelng machine, the combination of a jack post, a last bed piece having a flush surface bearing upon the end portion of the jack post and freely movable in a plane 110 transversely of the jack post, and a last plate having a flush surface bearing upon the last bed piece and movable in a plane parallel to the plane of movement of the last bed piece and in a direction at an angle to the direction of last bed piece movement, said last plate being provided with a last pin and a bearing surface to engage the top or crown 115 of a last.

9. In a heelng machine, the combination 120 of a jack post movable from an inoperative position to a fixed operative position, means for locating a shoe for operation thereon, a last bed piece having a flat bearing surface engagement with the jack post, and a last plate having on one face a flat bearing surface engagement with the last bed piece, said flat bearing surface engagements being constructed and arranged to permit the last plate to move in a plurality of directions in 125 130

a single plane as the shoe is placed in contact with the said locating means.

10. In a heelng machine, the combination of a jack post movable from an inoperative to a fixed operative position, means for locating a shoe for operation thereon, a last bed piece having a flat bearing surface engagement with the jack post, and a last plate having on one face a flat bearing surface engagement with the last bed piece, said flat bearing surface engagements being constructed and arranged to permit the last plate to move in a plurality of directions in a single plane as the shoe is placed in contact with the said locating means, said last plate having on its other face a last pin and a pressure bearing surface to engage the top or crown of a last.

11. In a heelng machine, the combination of a jack post movable from an inoperative 20 to an operative position, a means for locating a shoe thereon as the jack is moved to operative position, and a last plate carried by said jack post constructed and arranged to tilt and movable in a plurality of directions 25 in the same plane responsive to the said locating means as the jack is moved to its operative position to automatically position the shoe.

In testimony whereof I have signed my 30 name to this specification in the presence of two subscribing witnesses.
